[57] CLAIM

The ornamental design for a contact lens inserter, as shown and described.

DESCRIPTION

FIG. 1 is an environmental perspective view of a contact lens inserter showing my new design;

FIG. 2 is a front elevational view thereof;

FIG. 3 is a rear elevational view thereof;

FIG. 4 is a left side elevational view with the right side being a mirror image thereof;

FIG. 5 is a top view thereof; and,

FIG. 6 is a bottom view thereof.

The broken line showing of the person and the contact lens in FIG. 1 is for illustrative purposes only and forms no part of the claimed design.
